(57) **CLAIM**

The ornamental design for a connector device with surface feature, as shown and described.

DESCRIPTION

FIG. 1 is a top and side perspective view of a connector device with surface feature showing my new design;

FIG. 2 is a top plan view thereof; and,

FIG. 3 a cross-sectional view thereof, taken along lines “3—3” in FIG. 2.

The dash-dot-dot line in the figure drawings is included to show unclaimed portions only and forms no part of the claimed design. The even-broken line represents the boundary of the claimed design.
